UNITED STATES PATENT OFFICE.

WILHELM GALLENKAMP, OF MUNICH, GERMANY.

FIRE-EXTINGUISHER.

1,051,496.

Specification of Letters Patent. Patented Jan. 28, 1913.

Application filed April 10, 1912. Serial No. 889,739.

To all whom it may concern:

Be it known that I, WILHELM GALLENKAMP, a subject of the German Emperor, and a resident of Munich, Germany, have 5 invented certain new and useful Improvements in Fire-Extinguishers, of which the following is a specification.

In fire extinguishers containing the acid in a separate inclosed receptacle provided 10 with a solid stopper, made of glass or lead or similar material, not only is there danger of breaking the bottle when shaken, but the stopper is liable to stick and thus prevent the operation of the device at the desired 15 time. Such a stopper also requires extra room in the extinguisher, and projects undesirably near the discharge outlet. Moreover such stoppers are not always reliable and any absorption of water around them 20 causes undue dilution of the acid, in the case of sulfuric, and sometimes causes escape of the resulting diluted and expanded acid into the surrounding liquid, with resulting premature discharge of the extinguisher. The 25 diluted acid is also when weakened less able to withstand extreme cold and extreme climates. In the case of hydrochloric acid any escape of the acid might cause destruction of the metal of the vessel itself.

According to the present invention the 30 above-mentioned disadvantages are overcome. Instead of using such a solid stopper for the acid bottle there is used a stopper or upper layer of a suitable liquid which is 35 placed above the acid in the acid receptacle and separates it from the surrounding water or aqueous liquid containing the other ingredients of the extinguishing composition. This liquid which is placed in the upper 40 part or neck of the acid bottle, is of such a nature that it does not mix either with the acid, or with the other liquid (solution of bicarbonate), its specific gravity being between those of these two liquids. Thus with sulfuric acid, (sp. gr. 1.84), for example, carbon tetrachlorid could be used, its specific 45 gravity being 1.63; with hydrochloric acid, (sp. gr. 1.20), o-nitro-toluene (sp. gr. 1.163) could be used; or other suitable liquids hav-

ing similar specific gravities. These liquid 50 layers or liquid stoppers form a most intimate contact with the neck of the bottle, and thus prevent any mixing of the liquids above and below them; also any inoperativeness, due to sticking of a solid stopper, is avoided. 55 The provision of the liquid stopper of the present invention consequently gives an arrangement which is at the same time simple and reliable, and free from the disadvantages of the known solid stoppers. 60

The present invention is further illustrated by the accompanying drawings in which—

E is the vessel containing the water or aqueous solution of bicarbonate used for extinguishing, F the bottle supported by, and attached to, the vessel E, S the acid in the bottle, and T the stopper or plug or layer of liquid in the neck of the bottle forming a separating layer between the acid and the 65 aqueous layer above. The arrangement of the present invention offers the added advantage that the acid bottle can be, as shown, submerged in the aqueous liquid, without intermixing therewith. At the same time, 70 however, when the acid does escape it is prevented from escaping except through the liquid above it, and a thorough mixing, and a prevention of the escape of the acid itself, 75 is assured. The vessel is also in this way 80 protected from the direct action of the acid.

I claim:

1. In a fire extinguisher an acid bottle provided with a stopper in the form of a liquid non-reactive with the acid, and of 85 less specific gravity.
2. In a fire extinguisher a vessel containing an aqueous solution of bicarbonate, and an acid bottle submerged therein provided with a liquid stopper of a specific gravity 90 greater than that of the aqueous solution, but less than that of the acid.

In testimony whereof I affix my signature in presence of two witnesses.

WILHELM GALLENKAMP.
